UNITED STATES PATENT OFFICE.

ALBERT W. TANDY, OF LOS ANGELES, CALIFORNIA.

DESIGN FOR A SELLING BOOTH.

Application filed March 28, 1928. Serial No. 26,043. Term of patent 3½ years.

To all whom it may concern:

Be it known that I, ALBERT W. TANDY, a subject of the King of Great Britain, residing at Los Angeles, in the county of Los Angeles and State of California, have invented a new, original, and ornamental Design for Selling Booths, of which the following is a specification, reference being had to the accompanying drawing, forming part thereof.

The figure is a perspective view of a selling booth, showing my new design.

I claim:

The ornamental design for a selling booth, as shown.

A. W. TANDY.
